TRAVELING SUCTION TYPE FLOOR CLEANER
Agnew H. Bahnson, Jr., and James F. King, Jr., both of
1001 S. Marshall St., Winston-Salem, N.C.
Filed Apr. 18, 1960, Ser. No. 22,900
2 Claims. (Cl. 15—312)

This invention relates to suction type equipment for cleaning floors, particularly the aisle areas between adjacent rows of textile processing machines such as spinning frames, looms and the like. In a spinning room, for example, the improved suction type floor cleaner is arranged to travel overhead such as along a trackway located longitudinally of and above the frames. The cleaner may be self-propelled along the trackway or it may be constituted as a trailer unit coupled onto another type of self-propelled cleaner unit which is adapted to blow air downwardly in the direction of the spinning frame so as to clean off the latter and blow the lint onto the floor where it can then be picked up by the suction unit in accordance with the present invention.

The improved suction type floor cleaner may be constructed to clean only one aisle at a time but preferably is arranged as a dual unit which travels longitudinally of and above the frame, one unit cleaning the aisle floor adjacent one side of the frame and the other unit cleaning the floor of the next aisle adjacent the opposite side of the frame.

In accordance with the invention, the improved traveling suction type floor cleaner is comprised of a carriage which travels overhead in a direction longitudinally of the aisle, a suction trunk extending downwardly from the carriage into the aisle and terminating in a suction nozzle disposed adjacent the aisle floor, a storage trunk also extending downwardly from the carriage along side of the suction trunk for storing lint which is sucked up from the floor, this storage trunk preferably being provided with a normally closed discharge opening through which the stored lint and other particulate material can be removed periodically as the storage trunk fills, and fan means for creating the necessary suction in the suction trunk to draw up the lint and transfer it to the upper end of the storage trunk.

The suction fan can be of the centrifugal type having an impeller and scroll, in which case the upper end of the suction trunk is placed in communication with the air inlet to the impeller and the upper end of the storage trunk is similarly placed in communication with the air discharge point from the scroll. Thus lint laden air drawn upwardly through the suction trunk passes through the impeller into the scroll and thence into the upper end of the storage trunk. Preferably an upper portion of the wall of the storage trunk is made sufficiently porous to permit air to be discharged through it thus retaining the lint and other particulate matter in the storage trunk which then drops by gravity to the bottom and fills the storage trunk from the bottom up. This mode of filling the storage trunk, i.e. from the bottom up is of material assistance in packing lint into the trunk and hence increases its effective storage capacity thus lengthening the interval between successive clean-outs. Moreover, the long, comparatively large diameter storage trunk provides an

2

optimum volumetric capacity and the discharge opening at the bottom simplifies the problem of emptying. Also, the upper porous wall portion of the storage trunk may be made somewhat transparent so as to permit visual inspection of the interior and thus enable one to determine when the trunk needs to be emptied. The desired transparency can be established by making the porous wall portion from a mesh material which is of sufficient fineness to trap the lint and yet coarse enough to permit the air to flow through and one to also see through.

As an alternative, the upper porous wall portion may be relatively non-transparent so that it functions only to permit the flow of air therethrough and the desired transparency for visual inspection may be established by incorporating a window which can be made of any suitable transparent material such as glass or polyethylene sheeting.

When constructed as a dual unit for simultaneous cleaning of adjacent aisle floors at opposite sides of a row of textile processing machines, the traveling carriage supports a pair of cleaner assemblies disposed laterally outward from the track on which the apparatus travels, each such assembly including a fan, a suction trunk and a storage trunk. Preferably the fans are driven from a common motor located centrally on the carriage through suitable transmissions such as a belt drive.

The foregoing objects and advantages of the invention will become more apparent from the following detailed description of one practical embodiment thereof as applied to a dual unit for simultaneously cleaning the aisles on opposite sides of a row of spinning frames, and from the accompanying drawings wherein:

FIG. 1 is a view in top plan of the dual unit cleaner;

FIG. 2 is a view in side elevation of the cleaner in association with the spinning frame and with certain parts drawn in section;

FIG. 3 is an end view of the cleaner in association with the spinning frame;

FIG. 4 is a longitudinal view of the storage trunk with the discharge outlet opened;

FIG. 5 is a bottom plan of the storage trunk;

FIG. 6 is a view in elevation of the lower portion of the suction trunk including the suction nozzle; and

FIG. 7 is a view similar to FIG. 6 but taken at a right angle thereto.

With reference now to the drawings and in particular to FIGS. 1-3, the traveling cleaner is seen to be comprised of a carriage 10 which can be towed, but in the illustrated embodiment is designed as a self-propelled unit adapted to run overhead on a trackway 11 which extends longitudinally of a row of spinning frames, part of one such frame being indicated at S. The trackway 11 is conventional, being supported at intervals on posts 12 upstanding on the frame S itself. The details of the self-propelled carriage have not been included since they do not per se constitute any part of the present inventive concept. Moreover, various constructions for motorized carriages are already well known for use with traveling cleaners of other types adapted to blow off various parts of the spinning frames. Electrified conductor rails, not shown, extend parallel with the trackway, and collector shoes on the carriage, also not shown, run in contact with the rails so as to provide electric power for energizing the electric motor used to propel the carriage along the

trackway. These electrified rails and shoes are also conventional and hence have been omitted in the interest of simplifying the disclosure.

Located laterally outward to each side of carriage 10 is a casing 13 in which is supported a complete fan which is illustrated as being of the centrifugal type and which includes an impeller 14 and a scroll 15. The air discharge outlet 16 from scroll 15 is arranged tangentially and the air inlet 17 to the impeller 14 is arranged axially of the axis of rotation. Impeller 14 is mounted in suitable bearings for rotation about a vertical axis and the drive shaft 18 of the impeller extends upwardly through an opening in the top wall of the casing 13. A drive pulley 19 is secured to the upper end of drive shaft 18 and a belt 20 extends from pulley 19 to another pulley 21 located on the vertical drive shaft 22 of an electric motor 23 the rotor of which is mounted for rotation about a vertical axis. Motor 23 which is supported by a central part of the carriage 10 thus serves to drive the impellers 14 of both suction fans and can derive its power from the same electrified rails as are used to furnish power for propulsion of the carriage.

The bottom wall 13a of each casing 13 is spaced from the bottom wall of the scroll 15 as shown in FIG. 2 so that the space therebetween constitutes a plenum chamber 13b which is in communication with the air inlet 17 to impeller 14 of the suction fan. The bottom wall 13a of each casing also is provided with two circular openings. A connecting sleeve 24 is fitted into one of the openings and serves to support the upper end of a section trunk 25 which extends downwardly and terminates in a nozzle 26. This nozzle is provided with an elongated rectangular inlet 26a located closely adjacent the aisle floor F so as to draw in lint and other particulate material which may be on the floor as the suction trunk moves along the aisle. The long axis of the nozzle inlet 26a is placed transverse to the direction of motion of the trunk 25 so as to provide an optimum condition for taking up lint from the aisle. Various means may be provided for attaching the top of such trunk 25 to connection sleeve 24 and a conventional clamping strap 27 has been illustrated.

The suction trunk 25 is preferably made from a somewhat flexible material but which, however, has sufficient body to prevent collapse under suction. One suitable material is neoprene reinforced with wire and is sold under the trade name "Flexaust."

It will be noted from the drawings and from FIGS. 6 and 7 in particular that a short length of chain 28 is secured at one end to a ring type anchor plate 29 that is riveted to one wall of the nozzle 26 and is provided with a conventional snap hook 31 at the other end for fastening onto the lower end of a storage trunk 32.

Another connection sleeve 33 fitted into the other opening in the bottom wall 13a of each casing serves to support the upper end of the storage trunk 32 which extends downwardly along side of suction trunk 25. Trunk 32 serves to store lint which is drawn up through the suction trunk 25 into the fan and passed out of the scroll 15. While the entire storage trunk could be made from porous material so as to permit air to flow therethrough and trap the lint inside of it, it is preferred to restrict the porous section to the upper part thereof which would normally be located above the level of any obstructions such as a doffing and donning cart or the like which may be standing in the aisle as the cleaner moves along it. Thus the upper part of storage trunk 32 preferably consists of a porous material 34 such as a 30 x 40 Saran mesh which is reinforced at the top by a short cylindrical insert 35 of neoprene, and the latter makes a close sliding fit over connection sleeve 33 and may be secured tightly upon the same by a clamping strap 36.

The upper end of sleeve 33 is connected to the rectangular outlet from scroll 15 by means of a tubular transition 37 made from any suitable flexible material.

The tubular Saran mesh material extends to a point about forty to fifty inches or so from the floor and hence is protected against damage from obstacles in the aisle. Below the porous tubular portion 34 the storage trunk 5 is constituted by neoprene 38 or some similar material which is unlikely to become damaged by striking against obstacles in the aisle. The cross section of the lower neoprene portion 38 is generally cylindrical to a point near the bottom and there changes over to a rectangular configuration by means of a rigid rectangular frame 39 10 inset into the material and secured thereto.

Connected to each of the four sides of frame 39 is a flap 41 and these are adapted to be folded inwardly so as to overlap each other and close the bottom of the storage trunk 32. One of the flaps is provided with a staple 42 and the flap opposite thereto is provided with a complementary slot 43 through which the staple extends as the flaps are infolded. After infolding, the hook 31 on the end of chain 28 is then snapped in place 15 through the staple thus holding closed the lower end of the storage trunk. When the trunk 32 has become filled with lint, the suction cleaner unit is stopped, the lower end of trunk 32 opened and the lint drawn out of the bottom into a suitable receptacle. The diameter of the storage trunk is preferably made as large as practical so as to provide maximum storage volume. In one practical embodiment, the storage trunk has a diameter of 7" and the suction trunk a diameter of 5". The length of the trunks 25 and 32 are about 80". The advantages of 20 constituting the lint storage compartment for the cleaner as a tubular element along side of the suction trunk as distinguished from a storage compartment located elsewhere are that it provides a more practical and larger storage space thus lengthening the intervals between consecutive clean-outs and simplifying removal of the lint. Moreover, the upper portion of the trunk being of a mesh material is sufficiently transparent to permit visual 25 observation of the amount of lint stored. Also, the lint tends to drop by gravity and by the air pressure to the lower part of the trunk, thus filling the same from the bottom up and providing for optimum packing of the 30 lint.

In lieu of using a mesh type of material to develop 35 both porosity to air and transparency in the upper portion of the storage trunk, one might use an air porous but non-transparent type of material and establish the transparency by inserting a window into the wall thereof, such window being made of glass or a transparent plastic material such as polyethylene sheeting.

In conclusion it will be understood that while we have 40 described and illustrated one practical embodiment of our improved traveling type suction cleaner for aisle floors, the particular details may be departed from in various respects without departing from the spirit and scope of 45 the invention as defined in the appended claims.

We claim:

1. In a suction type device for cleaning aisle areas 50 between rows of textile processing machines, the combination comprising an overhead carriage movable longitudinally of the aisle, a suction fan on said carriage having an inlet and an outlet, a suction trunk extending downwardly in the aisle and connected at its upper end to the fan inlet, a suction nozzle at the lower end of said suction trunk adjacent the aisle floor, a storage trunk extending 55 downwardly in the aisle and connected at its upper end to the fan outlet, said storage trunk having a discharge opening at the lower end thereof constituted by interfolding flaps, one of said flaps being provided with a staple and another of said flaps being provided with a complementary slot to receive said staple, and means including 60 a chain secured to the lower end of said suction trunk and having a snap hook at the end thereof engageable with said staple for holding the flaps in their infolded position and for interconnecting the lower ends of said suction and storage trunks.

2. In a suction type device for cleaning aisle areas between rows of textile processing machines, the combination comprising an overhead carriage movable longitudinally of the aisle, a suction fan on said carriage having an inlet and an outlet, a suction trunk extending downwardly in the aisle and connected at its upper end to the fan inlet, a suction nozzle at the lower end of said suction trunk adjacent the aisle floor, a storage trunk extending downwardly in the aisle and connected at its upper end to the fan outlet, said storage trunk being of substantially the same length as said suction trunk, and means interconnecting the lower ends of said suction and storage trunks.
